CLAIM

We claim the ornamental design for a tree and shrub soaker ring, as shown and described.

DESCRIPTION

FIG. 1 is a perspective view of a tree and shrub soaker ring showing our new design;

FIG. 2 is a top plan view thereof;

FIG. 3 is a side elevational view thereof, the elevational view of the opposing side being identical thereto;

FIG. 4 is an end elevational view thereof;

FIG. 5 is an elevational view of the opposing end thereof; and,

FIG. 6 is a perspective view showing the tree and shrub soaker ring in use; the broken lines depict environmental structure for illustrative purposes only and form no part of the claimed design.
